UNITED STATES PATENT OFFICE.

JAMES A. WOTTON, OF MONTCLAIR, NEW JERSEY, ASSIGNOR TO WESTERN ELECTRIC COMPANY, INCORPORATED, OF NEW YORK, N. Y., A CORPORATION OF NEW YORK.

TELEPHONE-RECEIVER.

1,337,741.

Specification of Letters Patent. Patented Apr. 20, 1920.

Application filed November 3, 1917. Serial No. 200,055.

To all whom it may concern:

Be it known that I, JAMES A. WOTTON, a citizen of the United States, residing at Montclair, in the county of Essex and State 5 of New Jersey, have invented certain new and useful Improvements in Telephone- Receivers, of which the following is a full, clear, concise, and exact description.

This invention relates to telephone receivers and more particularly to those which 10 are used as auxiliaries to the usual receiver.

In telephone systems, it is often desirable to provide an additional receiver which the subscriber may employ as an auxiliary to 15 the usual receiver in listening to telephonic conversations when the sounds transmitted to the station are difficult to distinguish. Such auxiliary receivers are especially desirable for use in case the extraneous noises 20 surrounding the station are excessive or the quality of transmission over the connected lines is low.

In order to provide service of this character, it has been the general practice to 25 supply an auxiliary receiver usually of the watch case type, which is normally attached to the subscriber's set but which may be readily removed therefrom in case it is desired for use. While such an arrangement 30 provides a readily accessible receiver for auxiliary use, it has been found that when the auxiliary receiver is not in use, not only is the efficiency of the main receiver somewhat impaired due to the permanent in- 35 clusion of the auxiliary receiver in parallel relation therewith, but also objectionable howling sounds are often emitted from the auxiliary receiver, interfering materially with the telephonic conversation.

With a view of eliminating these difficulties, receivers of this character, in some instances, have been equipped with normally open switches mounted within, but operable from the exterior of the receiver, whereby 45 the auxiliary receiver may be included in circuit when desired. In such cases, however, it has been found that other objectionable noises have resulted due to the appreciable opening in the casing around the 50 operating member of the switch.

The object of the present invention is to provide a simple, compact and inexpensive receiver for this service which will overcome the difficulties experienced in the past.

55 To obtain this object in accordance with

a feature of the invention, the receiver is provided with a normally open switch located within but conveniently operable from the exterior of the receiver, the operating member of such switch substantially closing 60 the opening in the casing through which it passes.

This and other features not specifically mentioned above, will more clearly appear from the following specification and the 65 accompanying drawing, in which Figure 1 is a front sectional view of a receiver embodying this invention; Fig. 2 is a side elevation in section; and Fig. 3 is a perspective view of a portion of the receiver 70 showing the switching arrangement.

As shown in the drawing, a receiver embodying this invention comprises the usual shell or casing 1 externally threaded to receive the cap 2. Within the casing, the 75 usual permanent magnet 3 and the electro- magnets 4, 4 are mounted in operative relation to the usual diaphragm 5. Upon the upper surface of the permanent magnet structure, a plate 6 of non-magnetic ma- 80 terial is placed. A plate 7 is placed upon the plate 6 and a bank of contact springs comprising insulating members 9, 9, 9, rigid contact member 10 and resilient contact spring 11, is mounted on the member 7. 85 The parts 6, 7, 9, 10 and 11 are assembled with the permanent magnet structure by means of suitable screws 12, 12 and nuts 13, 13. A portion of the outer edge of mem- 90 ber 7 is formed to provide a knife edge ful- crum 14, upon which the substantially right- angled operating lever 15 rests. An aper- ture 16 is provided in the side of the casing to permit the extension of lever 15 to the outside of the casing where it is spoon 95 shaped so as to substantially conform to the contour of the casing. An insulating abut- ment 17 provided on the under side of spring 11, normally presses the short arm of lever 15 against the surface of plate 7 and 100 thereby holds the long arm of the lever 15 away from the exterior of the casing.

When the long arm of lever 15 is pressed against the exterior of the casing 1, the short arm of the lever is raised from the plate 7 105 and as a consequence, the normally disengaged contacts on spring members 9 and 10, are brought into engagement. Terminal lugs 18, 18 are provided on the opposite ends of contact springs 9 and 10, which terminals 110

may be suitably connected to so include the switch in the receiver circuit that the auxiliary receiver is brought into operative relation only while the switch is closed.

- 5 It will be noted that in any position of the operating lever 15 the aperture 16 in the casing 1 is substantially closed and that the exposed portion of the lever 15 is so shaped that it may be easily held against the casing during the periods in which the receiver is placed in the usual position for listening, while it does not at any time impair the appearance of the receiver.

10 What is claimed is:

- 15 1. In a telephone receiver, an annular casing having an opening in the side thereof, a member mounted within the casing and having a knife edge fulcrum located in such opening, an operating lever resting on said fulcrum and coöperating therewith to substantially close such opening throughout its operation, the short arm of said lever extending within said casing and the long arm thereof protruding from said casing and shaped to substantially conform to the exterior of said casing, and a plurality of contacts located within said casing and controlled by the actuation of said lever.
- 20 2. In a telephone receiver, a casing having an aperture in the side thereof, a knife edge fulcrum located within such aperture, a lever having a spoon shaped long arm projecting through such aperture and a flat short arm extending within said casing resting on said fulcrum and coöperating therewith to substantially close such aperture, a rigid contact carrying member, and a resilient contact spring carrying an insulating abutment in operative relation to
- 25 the short arm of said lever whereby the contact spring is caused to engage said rigid contact member upon the actuation of such spoon shaped portion of said lever.

- 30 3. In a telephone receiver, a casing having an opening in the side thereof, a knife edge

fulcrum extending from one edge of the opening, an operating lever having an arm extending within and an arm extending without the casing, the arms being joined by an arcuate intermediate portion one surface 50 of such portion resting on the knife edge fulcrum and another surface thereof slidably engaging the opposite edge of the opening, and a contact controlled by the lever.

55 4. In a telephone receiver, a casing having an opening in the wall thereof, a permanent magnet within the casing, a member mounted thereon and having a portion extending into the opening to provide a knife edge 60 fulcrum, a lever having an arm extending within and an arm extending without the casing, the arms being joined by an intermediate portion one surface thereof resting on the fulcrum and another surface slidably engaging one edge of the opening thereby coöperating with the fulcrum member to substantially fill the opening, and a plurality of contact members mounted on the permanent magnet and controlled by the 70 lever.

5. In a telephone receiver, a casing having an opening in the wall thereof, a plate member mounted within the casing and having a portion extending into the opening to 75 provide a knife edge fulcrum, a lever having an arm extending within and an arm extending without the casing, the arms being joined by an intermediate portion resting on the fulcrum and coöperating with the 80 fulcrum member to substantially fill the opening, a resilient member to maintain the interiorly extending arm of the lever normally in engagement with the plate member, and a contact controlled by the lever.

85 In witness whereof I hereunto subscribe my name this 30th day of October, A. D. 1917.

JAMES A. WOTTON.
